COMBINED GIRDLE AND BRASSIÈRE

Joseph Siegel, Detroit, Mich.; Marie F. Siegel
executrix of said Joseph Siegel, deceased

Application March 29, 1932. Serial No. 601,816

2 Claims. (Cl. 2—30)

My invention relates to new and useful improvements in women's garments, and more particularly to a combined girdle and brassière.

One of the objects of the present invention is to provide a girdle that will snugly hold the diaphragm in place, mold the hips to produce the slim girlish figure which is much desired, and snugly hold the busts to the figure.

Still another object of the invention is to provide a garment comprising a girdle and brassière, the brassière being so formed in conjunction with the girdle that it not only firmly fits the figure and snugly molds and cups the busts, but also leaves the entire back of the wearer uncovered, which is a style that is carried out in other garments, such as evening gowns and bathing suits, etc.

Still another object of the invention is to provide a garment comprising a girdle and an attached brassière, the latter being secured in the front to the girdle and preferably also at one end to the girdle while the other end is removably secured and designed to be fastened in a regular manner to the waist-line of the 25 girdle and at the rear thereof.

Still another object of the invention is to produce a garment consisting of a girdle and brassière wherein the entire back of the wearer is uncovered, with the exception of two small straps having forked ends that are attached to the garment in the rear, the forward ends of the straps being attached to the brassière and respectively over the busts.

Still another object of the invention is to produce a garment so arranged that the pull on the same from its different points will cause it to flare out slightly at the hip-line, so that the entire garment will snugly fit the figure and, at the same time, allow that freedom of movement, which is much to be desired.

With these and other objects in view, the invention consists in certain new and novel arrangements and combination of parts, as will be hereinafter more fully described and pointed out in the claims.

Referring now to the drawings,

Fig. 1 is a front view of the improved garment;

Fig. 2 is a rear view thereof and turned side

50 for side;

Fig. 3 is a side and rear view showing the garment in place;

Fig. 4 is a fanciful side and front view showing the manner in which the garment fits the 55 wearer;

Fig. 5 is an enlarged fragmentary sectional view taken on the line 5—5 of Fig. 2.

Referring now to a preferred embodiment, and for the moment to Figs. 1 and 2, which show a front and rear view respectively, there may be seen a girdle 1 and a brassière 2, the girdle being formed of a front portion 3 and a rear portion 4, the latter portion, of course, including the sides of the girdle. The front portion 3 has a central additional reinforcing panel 5 which may be provided with the small short stays 6 in its upper portion, this panel 5 being sewed on the inside of the garment. The lower portion 8 of the forward front panel is cut out, as well as the material in the front portion 3, and filled with 70 elastic 9, as may be seen in Figs. 1 and 2. Garter straps 10 are attached to the front lower edges of the garment, two of these being secured to the lower end of the front panel 5, so that the pull from these garters will be directed to a 75 reinforced part of the garment.

Along one edge (left of Fig. 2) of the front portion 3 of the garment may be seen a row of hooks 11 which are to be secured in the hook eyes 12 that extend down the other marginal 80 edge of the girdle.

Now along the other edge 13 of the front portion of the girdle there may be seen a strip of elastic material 14 to which, in turn, a marginal edge 15 of the rear portion of the garment is 85 stitched and there may be seen another elastic strip 14' attached to a marginal edge of the rear portion 4 of the girdle, so that when the garment encircles the figure these side strips of elastic material may stretch, thus allowing the girdle 90 to snugly fit over the hips of the wearer.

At the lower edge of the rear portion 4 of the garment there may be seen the additional garter straps 10', and it will be noticed that wherever the straps appear the garment is reinforced to 95 help sustain the strain from the said garter straps.

The lower marginal edge of the garment, both front and rear, is taped along its lower edge, as at 16, while the upper edge, that is, of the rear portion 4, is taped along its upper marginal edge, as at 17, and a further reinforcement occurs by taping along a line 18, as will be seen in Fig. 2.

It will be noticed that the elastic strip 14 105 extends upwardly to the line 19 while above this there is the inelastic material 20 which extends to the upper marginal edge 21 of the girdle.

The front portion 3 of the garment extends 110 slightly upwardly toward its center, as at 22,

and it will be understood that this upper marginal edge is also tapered, as may be seen at 23.

Now the left side of the girdle (Fig. 2) extends from its lower marginal edge up to the marginal upper edge 23, while outwardly extending from this side is a part of the brassière, which will shortly be described.

Thus far, it will be seen that considering just the girdle, it consists of the front inelastic portion 1, the rear inelastic portion 4 and the elastic inserts, the upper edges of the rear and sides of the girdle forming the waist-line of the girdle, the girdle, however, extending farther up the body of the figure in the front than it does in the rear.

Thus, the back of the wearer will be exposed as far as the girdle is concerned, whereas the front of the body (diaphragm) will be covered with the girdle to a point just below the busts.

Having described the girdle, a short description will follow of the brassière portion.

Still referring to Figs. 1 and 2, there will be noticed secured along the marginal upper edge 22 of the girdle the lace portion 24 of the brassière, which may have the usual little tucks 25, so that the lace will cup itself about the busts when on the wearer.

Now secured to the respective marginal side edge 26 of the lace portion of the brassière are the inelastic portions 27 and 44, which form the side portions of the brassière, and the portion 27, that is, to the left of Fig. 2, will first be described.

As will be seen, the lower edge 28 of the portion 27 is rounded upwardly slightly toward its outer end, while the upper marginal edge curves from the point 29 upwardly and around to the point 30. The inner edge of the material of the portion 27, as before mentioned, is secured along the edge 26 of the lace portion and also to the inelastic material of the front portion 3, as along the line 31.

About opposite the waist-line, the portion 27 is folded over, as at 32, and stitched along lines 33 to form a seam or dart.

It is, of course, desired to have the garment fit snugly at the waist and then flare slightly outwardly and downwardly to conform to the hips and also flare slightly upwardly from the waist to conform to the shape of the upper part of the human body. By forming a seam or dart in the brassière portion as above-mentioned, this is readily accomplished, as may be seen in Fig. 5, that is, by folding the material back on itself and putting stitching across the line, as shown, the garment fits into the waist and flares as just described. This forming of the dart in the opposite side of the brassière is also carried out, as will be seen in Figs. 1 and 2.

At the end of the brassière portion just referred to, that is the portion 27 to the left (Fig. 2), there will be seen the two little tapered elastic strips 35 and 35' which are reinforced and joined by a small piece of tape 36 with the two hooks 37 thereon.

Still referring to Fig. 2, there will also be seen a small reinforcement of tape 38 where the inner ends of the elastic strips join the outer edge of the material. At the upper end of this strip 38, there will be seen a shoulder strap 40 which is fastened at the point 29 and is also secured at its other end to the front of the brassière at the point 41 which is about over one of the busts.

There will also be seen the short strap 42 joining the shoulder strap which also connects with the upper marginal edge of the brassière, as at

43, so that in reality this shoulder strap 40 is forked at its lower end.

Now the other side of the brassière (Fig. 2) is substantially the same, that is, there is the portion 44 which has the small elastic end 45 but in this instance the elastic strip is sewed, as at 46, to the upper edge of the rear portion 4 of the brassière. There may also be seen two small hook eyes 47 to receive the aforementioned hooks 37 on the opposite ends of the brassière.

It will be understood that these hook eyes 47 might be sewed to the end of the elastic portion 45 and the portion 45 not permanently attached to the garment, but I find it preferable to attach this side of the brassière to the garment, as shown.

Around the entire upper marginal edge of the brassière, there will be a strengthening tape, so that the same will withstand the strain to which the garment is subjected.

It will be seen that there is also, of course, a shoulder strap on this side of the garment 48 and this has a similar strip 49 extending from the shoulder strap over to a point about midway of the length of the material 44 of this side of the brassière.

Referring for the moment to Fig. 3, where the garment is shown on the figure, it will be seen that the entire back of the wearer is exposed and that all that are seen are the two shoulder straps 40 and 48 and the little forked ends of the same, that is, the little straps 42 and 49.

The shoulder straps 40 and 48 will be of elastic and the little cross straps 42 and 49 may or may not be of elastic.

It will also be seen that the brassière portion overlaps the girdle portion around under the arms, so that there is no danger of the brassière riding over the girdle at these points. The back, however, is exposed as from this point upwardly under the arms, the brassière slants increasingly upwardly until it reaches the busts where it molds them tightly to the figure.

By providing the rear ends of the brassière with elastic and fastening one end permanently to the back and hooking the other end to the back, the brassière will always snugly and smoothly mold and fit the figure.

Furthermore, there will be an upward pull on the shoulder straps from a point directly in the center of the back and there will also be a pull under the arms from the shoulder straps to the brassière, so that the brassière under the arms will not only be held up in the front but will be pulled snugly toward the rear or, in other words, mold the figure.

By forming the sides of the brassière, that is, the portions 27 and 44 with the seam or dart, it will be seen that the effect is that the pull from the elastic fits the garment into the figure perfectly at the waistline and side and makes the lower part of the dart flare out over the hips and the upper part flare up and out toward the bust line.

From the foregoing, it will be seen that I have formed a garment consisting of a brassière and girdle that molds the diaphragm, snugly hugs the busts, molds the hips, fits perfectly at the waist-line, leaves the back of the wearer exposed and, at the same time, is so formed that the several parts will always snugly and smoothly fit the figure.

It will also be seen that the pull from the shoulder straps is evenly divided just below the armpits and in the rear of the garment, so

that the brassière will at all times be firmly held against the figure, even though there is no horizontal strap or horizontal rear ends of the brassière extending across the back above the 5 waist-line.

It will be understood that should it be desired to have the brassière extend somewhat higher in the back, the elastic straps forming the outer ends of the brassière might be made wider.

10 Many slight changes being possible in the construction hereinbefore set forth, I do not wish to limit myself to the exact details thereof.

Having thus described my invention, what I claim as new and desire to secure by Letters 15 Patent is:—

20 1. A combined girdle and brassière comprising a front panel of inelastic material, side panels of elastic material and a rear portion of inelastic material, the marginal edges of said related parts being reinforced with tape, the brassière forming a part of the girdle in the front and having two side portions extending outwardly from said panel, one of said side portions being rigidly attached to the back of the 25 girdle at its upper marginal edge, the other side portion of the girdle being unattached, elastic strips at the ends of the side portions of the brassière, horizontal seams extending across the side portions of the brassière and in a line with 30 the upper marginal edge of the rear of the girdle to thus cause the brassière to flare out-

wardly from the said seams, the side portions of the brassière being cut sharply from their upper edges to their outer ends, shoulder straps having the respective ends of their front portions secured to the front of the brassière and the ends of their rear portions secured to the side portions of the brassière near the outer ends of said side portions, and straps extending from a point substantially midway the height of the said side portions of the brassière to said rear portions of said shoulder straps thus causing the brassière to be pulled tightly in about the figure of the wearer.

2. A combined girdle and brassière, the brassière comprising a front and side portions, the side portions having a double thickness of material along a line just above the hips of the wearer, when the garment is in place, to allow the brassière to flare outwardly in both directions from said line just above the hips to thus mold the sides and rear of the garment to the figure, shoulder straps extending from the front portion of the brassière to the ends of the side portions, means also for connecting the sides of the brassière to the said shoulder straps at a point remote from the ends of said shoulder straps whereby said shoulder straps not only support the brassière in the front but pull the brassière beneath the arms and toward the back snugly about the wearer.

JOSEPH SIEGEL.
